UNITED STATES PATENT OFFICE.

ALBERT SCHINKEZ, OF CHARLOTTE, MICHIGAN.

ROTARY-CYLINDER EXPLOSIVE-ENGINE.

1,007,240.

Specification of Letters Patent.

Patented Oct. 31, 1911.

Application filed December 12, 1910. Serial No. 596,963.

To all whom it may concern:

Be it known that I, ALBERT SCHINKEZ, residing at Charlotte, in the county of Eaton and State of Michigan, have invented a new and Improved Rotary-Cylinder Explosive-Engine, of which the following is a specification.

My invention, which relates generally to that type of internal combustion engines in which the working cylinders rotate about a stationarily held crank shaft, primarily has for its object to provide an engine of the general type stated, in which the operating parts are so designed whereby the engine will develop a maximum efficiency by reason of the compact arrangement of a few co-operating parts, capable of being economically manufactured, readily assembled and in which special provision is made for positive and uniform explosive actions in the several independently acting working cylinders.

My invention, in its generic nature, comprises an improved construction and arrangement of parts so combined to produce a four cycle type of engine, adapted especially for driving propellers of air craft, and in its more subordinate features, my invention consists in certain details of construction and peculiar combination of parts, all of which will be hereinafter fully explained, specifically pointed out in the appended claims and illustrated in the accompanying drawings, in which:

Figure 1, is a perspective view of a complete engine constructed in accordance with my invention. Fig. 2, is a face view of the cam disk that controls the valve shifting rods hereinafter explained. Fig. 3, is a vertical longitudinal section of the machine shown in Fig. 1. Fig. 4, is a face view of that end having the radial hollow arms or ports. Fig. 5, is a transverse section of the engine and shows the general relation of the pistons in the several engines. Fig. 6, is a detail view of the hub member that is fixedly held on the shaft.

As hereinbefore stated, a prime object of my invention is to provide an improved construction and arrangement of parts constituting a rotary motor so designed that the same can be readily utilized for driving aeroplanes, in the practical operation of which the greatest desideratum is a minimum weight of the driving mechanism under a maximum efficiency or thrust power.

In carrying out my invention and as shown in the drawings, the crank shaft I is held stationary and upon it are rotatably mounted a plurality of working cylinders A, 60 each of which are of like construction with the several piston and crank rod connections, relatively so arranged that the firing or explosive operations are effected in alternate succession, that is to say, if there are five 65 cylinders the explosion after occurring in the first or No. 1 cylinder, next occurs in No. 3 cylinder, while No. 2 is exhausting; No. 4 is drawing in a new charge and No. 5 is making its thrust under a prior explosion, 70 the thrust, or impelling motion being one hundred and eighty degrees or from the point O to point N indicated in Fig. 4 of the drawings.

Referring now more particularly to Fig. 3 75 of the drawing, which shows one of the working cylinders and the valve actuating means therefor, in its complete form, i designates the crank of the shaft I, B the piston rod that couples the crank i with the piston 80 C that operates in its respective cylinder A, it being understood the walls of the several cylinders A radiate from and form a part of a hub-like casing A' that includes an axial or forwardly projected member M that 85 forms a socket for the outer end of the shaft I and to which the propeller X is fixedly connected when the engine is utilized for aeroplanes and the like.

The hub or casing A' that carries the cylinders A has an axial opening a' at the inner side to provide for the desired adjustment of a cam disk K, the construction of which is best shown in Fig. 2.

The cam disk K is fixedly mounted on the 95 shaft I and its function is to control the opening and closing of the fuel feed and the exhaust or residuum gases to and from the cylinders as will presently be fully described.

Cooperatively joined to and rotatable with 100 the several cylinders A are the combined intakes and exhausts in the nature of hollow arms G—G and these radiate from a ring G' that rides upon the annular flange h on an inside hub H that is fixedly mounted on the 105 shaft I. A long bearing sleeve P loosely mounted on the shaft I is located within the hub H and the said sleeve has an annular enlargement or end disk p' which is bolted to the frame that carries the cylinders A so 110 as to turn therewith.

The cam disk R before referred to has a

pair of annular grooves, an inner one K^2 and an outer one K' and with these grooves co-operate stub pins p one of which is provided for each of the cylinders and each of which 5 controls the shifting adjustment of the single valve D hereinafter again referred to. The stub engaging grooves K^2 and K' are concentrically arranged except at a predetermined point where the said grooves join 10 and form cross-overs k' and k^2 , the purpose of which will presently appear.

The several stud pins p engage the grooves in the cam plate and to each of the pins is pivoted the lower end of a valve shifting rod F , the outer end of which is guided through apertures in the outer or angle ends g of the hollow arms or ducts G , which ends, as is clearly shown in Fig. 3, extend over the single ports a in each of the 20 working cylinders, controlled by a single valve D that is moved outwardly to and held closed by the internal pressure within the cylinders and which is mechanically shifted by a rocker lever E , one of which is mounted on each of the angle ends g of the arms G and one end of which engages the outwardly projected stem d' of the valve D while the other end engages the outer end 25 of the valve shifting rod F .

30 By referring now more particularly to Fig. 4 it will be seen that flange h of the fixedly held hub H has an annular exhausting port that extends one hundred and eighty degrees, the entire upper half of the 35 hub, which hub, it should be stated, in practice, is made of two half sections. The lower part of the ring has an inlet port that extends one half the distance between the diametrically opposite ends of the exhaust 40 opening, that is, between the beginning and ending points thereof.

By reason of the peculiar arrangement of the parts described and particularly that of the hub H with the exhaust and intake 45 ports and the single cam disk with the double grooves and the single valve feature for each cylinder, a very simple, inexpensive and easily controlled, as also a positively operating, actuating mechanism is 50 provided.

The manner in which the invention operates will best be understood by referring particularly to Figs. 2, 4 and 5. Considering the piston of cylinder number 1 as having 55 a compressed working charge ahead of it, said cylinder is just in the position it assumes at the time of ignition. At this time the valve D is held closed by the force of expansion of the fired mixture. As soon 60 as the cylinder number 1 has passed the firing point it moves from the position shown in Fig. 5 in a counter-clock-wise direction under the force of the exploded mixture, until it reaches a position diametrically opposite to the position in which it is shown in 65

Fig. 5, at which time the cylinder number 1 will have arrived opposite the point N in Fig. 4 so that the exhaust port will be in communication with the duct G so that as the cylinder 1 moves from position N to 70 position O it will exhaust. While the cylinder number 1 is moving from the position shown in Figs. 5 and 4 around to a diametrically opposite position, the pin p rides in the groove K^2 so as not to affect the valve D . As 75 soon however, as the cylinder passes the point N in Fig. 4, the pin p crosses into the outer groove K' and opens the valve D , thereby permitting the spent gases to exhaust, as the cylinder moves from position 80 N around to position O in Fig. 4. The cylinder number 1 having made a complete revolution from the position in which it is shown in Fig. 5, moves again from the position shown in Fig. 5 to a point diametrically 85 opposite to such position, while the pin p travels in the outer groove K' and holds the valve D open so that as the cylinder passes the port J it will receive fresh working agent. The cylinder number 1 having 90 reached a position diametrically opposite that in which it is shown in Fig. 5, the pin p is now switched back into the groove K^2 to permit the valve D to be held closed as the piston compresses the charge during 95 the movement of the cylinder from the opposite direction to that in which it is shown in Fig. 5 back to the starting position in which the cylinder is shown in Fig. 5. The operation of the other cylinders is precisely like 100 that explained for the first cylinder fired.

While I have shown and described the engine as equipped with five working cylinders and cranks, it is obvious a lesser or a greater number of cylinders may be employed, and further, while I prefer to have the crank shaft stationary and the cylinders rotate about the shaft, the generic feature of my invention would appear were the shaft held to rotate and the cylinders fixedly 110 secured.

I am aware that rotatable cylinder engines with mechanism for successively controlling the valves for the several cylinders have been heretofore provided. My invention, so far as I know, differentiates from what has heretofore been provided in this art in the manner in which the cylinders, each with but a single combined inlet and exhaust port, are combined with the shaft 115 and a relatively stationarily held means for mechanically setting and positively holding the valve to its open positions while exhausting and while drawing in a new charge. Again, by providing a series of hollow arms 120 that radiate from and have an axial bearing on a long hub at the inside of the crank end of the shaft, a long rotary bearing for the member to which the valve shifting rods are connected is also provided for, in such 130

manner that great stability of the valve actuating means is effected, and with the use of a minimum amount of ports and without the need of springs or spring actuated shifting means such as are generally necessary in the forms of engines of this type heretofore provided.

The parts are of a simple arrangement and their construction is such that they can 10 be easily assembled for use and economically made.

Special means for carbureting or vaporizing a liquid working fluid have not been shown further than a feed opening is indicated in the drawings as in connection with the intake through the hub flange *h*, it being understood that any suitable working agent feeding means may be used in connection with the mechanisms herein 20 shown and described in detail.

What I claim is:

1. In a motor of the class described, the combination of a plurality of working cylinders each having a single valved port for 25 the intake and exhausting of the working charge, a piston for the cylinder and a crank shaft, the latter and the cylinder having a relatively rotary motion; of a single means actuated by the said motion for holding all 30 of the valves of the aforesaid ports open during the suction and exhausting strokes of the respective pistons, and a single fuel supply and exhaust distributing valve common to all of said cylinders, and an individual duct for each cylinder for effecting communication between the respective port valves and said common distributing valve mechanism.

2. In a motor of the character described, 40 a stationary crank shaft, a cylinder rotatably mounted on the shaft, having a power transmitting axial member, and a single valved port for the passage of the working and exploded charges, a duct rotatable with 45 the cylinder, an exhaust and fuel inlet with which the mouth of the duct alternately comes in communication as it rotates with the cylinder, said duct having a discharge that communicates with the valved port in

the cylinder, and a means including a shift- 50 able cam actuated member for holding the valve to the cylinder open as the mouth of the duct passes over the fuel intake and the exhaust.

3. In a four cycle reversely rotatable engine, a cylinder having a single valved port for admitting the inlet of the working charge and permitting the exhausting of the burned mixture, the working piston and the crank shaft; of a disk fixedly held with 60 respect to the cylinder, said disk having a pair of annular concentric grooves joined at one point to form a double cross-over, a rod having a pin for engaging the grooves and a rocker mounted on the cylinder for 65 engaging the valve in the cylinder port.

4. A rotary explosive engine of the four cycle type that comprises the following elements in combination, a stationary crank shaft, a cylinder that radiates therefrom, a 70 casing rotatably mounted on the shaft and carrying said cylinder, said cylinder having a single valved port, for admitting a working charge and exhausting a burned charge, an axial power transmitting member on the cylinder, a divided hub having inner and outer annular flanges fixedly mounted on the shaft, the outer flange having an exhausting opening and an oppositely positioned fuel intake opening, a duct whose mouth rides 80 upon and closes over the annular flanges of the hub, said duct having a single discharge that opens into the valved port on the cylinder, a disk fixed on the shaft having an inner and an outer annular groove, 85 the said grooves being joined by a cross-over, a sleeve rotatably mounted on the shaft within the flanged hub, and provided with an annular flange, a pin that projects from the flange and engages the groove in 90 the disk, a rocker for engaging the valve and a rod hinged to the pin and having its free end in engagement with the rocker.

ALBERT SCHINKEZ.
